UNITED STATES PATENT OFFICE.

THEODORE MILLER, OF DETROIT, MICHIGAN.

DESIGN FOR A STOVE.

SPECIFICATION forming part of Design No. 23,427, dated July 3, 1894.

Application filed April 5, 1894. Serial No. 508,502. Term of patent 7 years.

To all whom it may concern:

Be it known that I, THEODORE MILLER, a citizen of the United States, residing at Detroit, county of Wayne, State of Michigan, have invented and produced a new and original Design for Stoves; and I declare the following to be a full, clear, and exact description of the invention, reference being had to accompanying drawing, which shows a part thereof.

The drawing is a view in perspective of a stove showing my design.

The leading features of my design consist of an ornamental leg frame A, an octagonal tank chamber B, a combustion chamber C, an ornamental rim D forming the covering of the tank chamber and located at the base of the combustion chamber. Above the combustion chamber is a cylindrical drum E surrounded by a dome shaped ornamental top F. The leg frame is shown ornamented with scroll work, the tank chamber B is of plain sheet metal, and the lower portion of the rim D is shown ornamented with vertical flutings, the upper portion of the rim being mainly ornamented in the same manner, the front of the rim, however, constituting a name plate.

D' and D² represent ornamental side bars or handles.

The leg frame and the rim D at the corners of the stove are united by ornamental columns "b," spaced from the tank chamber and exterior thereto.

At the corners of the combustion chamber are vertically extended flues C' curved upon their outer faces and ornamented. The lateral faces of the flues are plain. Between the flues are the door frames "c."

Above the combustion chamber is an ornamental rim C² through which project the upper extremities of the flues C', said upper extremities being ornamented.

The drawing shows the front and one side of the stove.

The leg frame is essentially square in form, the corners, however, being rounded. The four legs A' are ornamented, their ornamentation extending up over the corners of the leg frame.

At the top of the dome F is an ornamental urn G. The dome shaped top F is formed with a row of holes as at "f" above the ornamental rim f', a second row of holes f² being provided thereabove, and open work, as shown at f³, below the base of the urn G, the upper portions of the legs extending upward at the base of the columns "b," said columns provided at their base with laterally projecting ornamental wings b'. The upper ends of the columns are provided with fluted collars b².

It will thus be observed that the chief features of my design as hereinbefore described and as herewith illustrated, consist in the form of the base, the combustion chamber, and the cylindrical drum surrounded by the dome shaped top.

What I claim as my invention is—

The design for a stove substantially as herein shown and described.

In testimony whereof I sign this specification in the presence of two witnesses.

THEODORE MILLER.
